TRACKWAY TURNABOUT FOR TOY VEHICLES

Cecil F. Adickes, Playa Del Rey, Calif., assignor to
Tonka Corporation, Mound, Minn.

Filed May 1, 1970, Ser. No. 22,763

Term of patent 7 years

Int. Cl. D21—02

U.S. Cl. D34—15

FIG. 1

FIG. 2

FIG. 3

FIG. 8

FIG. 1 is a front perspective view of a trackway turnout for toy vehicles showing my new design; and

FIG. 2 is a top plan view thereof;

FIG. 3 is a rear perspective view thereof;

FIG. 4 is a front elevational view thereof;

FIG. 5 is a rear elevational view thereof;

FIG. 6 is a left side elevational view thereof;

FIG. 7 is a top rear perspective view thereof;

FIG. 8 is a bottom plan view thereof.

I claim:

The ornamental design for a trackway turnout for toy vehicles, as shown.
